Assistant Examiner — Aula Soroush

(57) **CLAIM**

The ornamental design for an ecological aquarium as shown and described.

DESCRIPTION

Fig. 1.1 is a perspective view of a first embodiment of an ecological aquarium showing the design;

Fig. 1.2 is a front elevational thereof, wherein the rear elevational view is a mirror image thereof;

Fig. 1.3 is a left side view thereof, wherein the right elevational view is a mirror image thereof;

Fig. 1.4 is a top plan view thereof;

Fig. 2.1 is a perspective view of a second embodiment of an ecological aquarium showing the design;

Fig. 2.2 is a front elevational thereof, wherein the rear elevational view is a mirror image thereof;

Fig. 2.3 is a left side view thereof, wherein the right side view is a mirror image thereof; and

Fig. 2.4 is a top plan view thereof.

The broken lines form no part of the claimed designs.

1 Claim, 8 Drawing Sheets
